UNITED STATES PATENT OFFICE.

JOHN HENRY WALKER, OF LEXINGTON, KENTUCKY.

TROLLEY.

SPECIFICATION forming part of Letters Patent No. 732,145, dated June 30, 1903.

Application filed November 20, 1902. Serial No. 132,104. (No model.)

To all whom it may concern:

Be it known that I, JOHN HENRY WALKER, a citizen of the United States, and a resident of Lexington, in the county of Fayette, in the State of Kentucky, have made certain new and useful Improvements in Trolleys, of which the following is a specification.

My invention is an improvement in trolleys, and has for an object, among others, to provide novel means whereby to support the trolley-wheel, to prevent the wire from dropping immediately alongside said wheel, and for securing a more effective conduction of the current from the wheel and along the pole; and the invention consists in certain novel constructions and combinations of parts, as will be hereinafter described and claimed.

In the drawings, Figure 1 is a plan view of a trolley harp and wheel provided with my invention. Fig. 2 is a sectional view thereof. Fig. 3 is a detail perspective view of the guard-finger and its supporting-ring. Fig. 4 is a side elevation, partly broken away, of the harp and wheel. Fig. 5 is a detail side elevation of the front end of one of the prongs. Fig. 6 is a detail perspective view of one of the end nuts. Fig. 7 is a detail perspective view of one of the bearing-screws. Fig. 8 is a detail perspective view of one of the contact-plugs. Figs. 9 and 11 are detail perspective views of the sections of the boxing. Fig. 10 is a detail perspective view of the spring for closing the opening for the inlet of oil. Fig. 12 is a detail perspective view of the wheel-shaft; and Figs. 13 and 14 illustrate in section and elevation a somewhat different construction from that shown in Figs. 2 and 6 to 12, inclusive.

In carrying out my invention I employ a trolley-wheel A, which may be of any approved design and which fits on the middle portion B' of a shaft B. This shaft B may be of steel or other suitable material and has at its center a slightly-enlarged portion or boss at B', on which the wheel A may be secured by hydraulic pressure or otherwise, as may be desired. The wheel A may be of copper or suitable composition and forms a copper contact at C' with a conductor C, which is secured within the bore b of the shaft B, the shaft B being bored from end to end, as shown in Fig. 2, and a copper plug C being

fitted therein and having a branch C' projecting through an opening b' in the boss B' of the shaft B. In practice the branch C' is 55 preferably formed to project slightly beyond the surface of the boss B', so that the wheel when forced on the boss B' by hydraulic or other pressure will form a wiped contact with the projecting portion C' of the copper plug, 60 thus producing a practically perfect union with the plug and increasing the conductivity of the joint between the wheel A and the copper plug in the shaft, as will be understood from Figs. 12 and 2 of the drawings. 65

By the described construction I provide a shaft for the wheel, support the wheel thereon, and secure an efficient conduction between the wheel and shaft, as desired. The ends of the bore b of the shaft are threaded 70 to receive the bearing-screws D, which are of copper and thread into the ends of the shaft B and directly into contact with the opposite ends of the plug C, as shown in Fig. 2. These screws D project a short distance from 75 the ends of the shaft B and journal in the contact-plugs E, which are pressed into the openings in the opposite ends of the devices F for supporting the wheel-shaft and form a contact with said devices F at their outer 80 edges, as shown at E', and contact at their inner edges at E'' with the screws D, which turn in the said plugs, as will be understood from Fig. 2.

As shown and preferred, the devices F for 85 supporting the shaft of the wheel A are lubricating-boxes composed of inner sections F' and outer sections F'', the outer section F'' having a cup F³ rabbeted at its open edge f³, an opening F⁴, through which oil may be introduced, and a spring F⁵, secured at f⁵ in the cup F³ (see Fig. 2) and pressing at its free edge outwardly against the inner side of the opening F⁴ to close the same, as will be understood from Figs. 2, 9, and 10, and arranged to be pressed inwardly by the nozzle of an oil-can when it is desired to fill the cup F³ with oil. At its outer end the cup F³ has a tubular extension G, which fits in the end slot H' of the harp-prong H and is threaded 90 at G' to receive the end nuts I. (See Fig. 6.) The inner section F' of the oil-box has an end plate f' to fit in the rabbet f³, and a tubular portion f², which fits at its extremity f⁴ in a

rabbet f^6 , formed in the outer end plate of the outer section F^2 , as shown in Fig. 2 of the drawings, thus forming an oil-receptacle at F^6 between the tubular portion f^2 and the body of the section F^2 , as best shown in Fig. 2. The tubular portion f^2 is slotted at f^7 and may receive a wick or other absorbent filling by which lubricant supplied to the chamber F^6 can be fed by capillary attraction to the wheel-shaft B, as will be understood from Figs. 1 and 12 of the drawings.

The tubular portion f^2 of the section F^2 of the boxing forms a bearing in which turns the shaft B, as will be understood from Fig. 15 2 of the drawings, and the contact-plugs E may be pressed firmly in against the ends of the shaft B, as shown in the said Fig. 2.

The outer plates of the boxings are notched at J to receive the ends of the branches K' 20 of the conductor-wire K for the passage of the current from the wheel A to the motor on the car. These branches K' fit against the inner sides of the harp-prongs and at their ends in the notches J in the outer ends of 25 the supporting devices F for the trolley-wheel shaft and form electrical connections with said devices F, which through the medium of the copper contact-plugs E and the screws D connect with the contact-plug C in the 30 wheel-shaft, such plug being in electrical contact with the wheel, as before described.

The harp has its prongs H provided at their free ends with the slots H' and adjacent thereto with the openings H^2 , and the tubular extensions G of the devices F for supporting the wheel-shaft fit in said slots and also within the central openings L' of the rings L^2 of the guard-fingers L and receive at their threaded ends G' the end nuts I, as shown in 40 Figs. 1 and 2.

The guard-fingers L are provided at their inner ends with rings L^2 , which encircle the tubular extensions H and have studs l^2 , which project into the openings H^2 in the harp-prongs, the ring being provided at L^2 with a rib which fits in the slot H' of the prong H and prevents the finger L from turning, and such finger L projecting inwardly toward its point L' with such point lying close to the 45 surface of the wheel and the finger sloping thence outwardly in such position as to prevent the trolley-wire from coming in contact with the boxes which support the wheel-shaft.

55 The harp-prongs H are connected at h by a screw M, having a head M' at one end and receiving a nut M^2 at its other end, by adjusting which the free ends of the harp-prongs may be caused to bear with greater or less 60 tension on the opposite ends of the boxes F, as will be understood from Figs. 1 and 2 of the drawings.

By the described construction it will be seen I secure ample conduction for the current 65 between the trolley and the motor by means of the wire K, whose branches K' connect with the supporting devices F of the

wheel-shaft, which boxes may, like the plugs E' and screws E^2 , be made of copper or suitable composition having a high degree of 70 conductivity and tending to establish communication between the plugs C and the wires by which the current is conducted between the wheel and the motor, thus avoiding any heating of the trolley-pole and any 75 injury to the trolley-wheel because of the failure to carry off the current and also aid in securing high power and speed, as desired.

In Figs. 13 and 14 I illustrate a somewhat different construction in which the shaft 1 80 for the wheel is supported on a rod 2, which is supported in a bearing-block 3, which projects outwardly through a slot 4 in the harp 5 and receives the end nut 6, the finger 7 having its ring 8 interlocked by means of a 85 stud, such as l^2 , (shown in Fig. 3,) and the lug L^3 (shown in the same figure) with the harp-prong and being secured by the nut 6, as shown. In this construction the wheel 90 turns on the shaft 1, which is supported on 95 and fixed to the rod 2, and it will be noticed that the guard-finger 7 has its ring interlocked with the harp-prong and secured in such interlocking engagement by the end nut 6, threaded on the end of the tubular extension of the devices for supporting the wheel-shaft, in somewhat similar manner to that carried out in the construction shown in Figs. 1 and 2.

Having thus described my invention, what 100 I claim as new, and desire to secure by Letters Patent, is—

1. The improvement in trolleys herein described comprising the harp having its prongs provided with end slots and adjacent thereto with openings for the studs of the finger-rings, the fingers projecting at their points adjacent to the wheel and having the rings provided with lugs fitting in the slots of the prongs and with studs fitting in the openings adjacent to 110 said slots, the wheel, the wheel-shaft having a bore and an opening leading thence to the surface of the shaft and the copper plug in said bore and having a branch projecting in said opening to the surface of the shaft in 115 contact with the wheel, the supporting devices having bearings for the shaft and outwardly-projecting tubular portions projecting through the slots in the prongs and the openings in the finger-rings, the end nuts on 120 said tubular extensions and adjusted against the finger-rings, the contact-plugs fitting in the tubular extensions of the wheel-supporting devices and having end openings in line with the bore of the wheel-shaft, the screws 125 projecting through said contact-plugs into the ends of the wheel-shaft and in contact with the plug therein, and the conductor-wire having branches in contact with the bearing devices for supporting the wheel-shaft all substantially as and for the purpose set forth. 130

2. The combination with the harp-prongs having end slots and the wheel having a shaft, of devices provided with bearings for the

wheel-shaft and having outwardly-projecting tubular extensions fitting in the slots of the harp-prongs, the fingers projecting at their points adjacent to the wheel and having rings fitting around the tubular extensions of the wheel-supporting devices, and also provided with lugs fitting in the slots of the harp-prongs, and the end nuts on the tubular extensions and securing the same and the rings 5 of the fingers substantially as set forth.

3. The combination of the wheel, the wheel-shaft having a bore for the copper plug and an opening leading therefrom to the surface of the shaft for the branch of said plug and 10 the copper plug fitting in the wheel-shaft and having a branch projecting through the opening in the shaft to the surface thereof in position to contact with the wheel applied to the said shaft substantially as set forth.

4. The combination of the harp-prongs having end slots, the wheel and its shaft, the devices having bearings for the wheel-shaft and tubular extensions projecting into the slots of the harp-prongs, the guard-fingers interlocking 15 with the harp-prongs, and the end nuts engaging with the tubular extensions of the wheel-supporting devices and operating to secure the guard-finger rings in interlocking engagement with the harp-prongs substantially as set forth.

5. The combination with the wheel and its axle having a contact-plug provided with the portion contacting with the wheel, said shaft also having end openings leading to the contact-plug, the devices for supporting the wheel having a bearing for the shaft, the contact-plugs fitting in said supporting devices, and the screws fitting in the contact-plugs and extending into contact with the contact-plug in the shaft substantially as set forth.

6. The combination of the wheel, its shaft having a contact-plug provided with a branch leading into contact with the wheel, the boxes having bearings for the wheel-shaft and outwardly-projecting tubular extensions, the

contact-plugs fitting in said boxes, the screws projecting through said plugs into the ends of the shaft and into contact with the contact-plug therein and the harp-prongs supporting the tubular extensions of the boxes, substantially as set forth. 50

7. The combination of the wheel, its shaft, a contact-plug in the shaft and provided with a branch leading into contact with the wheel, contact-screws projecting into the ends of the shaft and into contact with the plug therein, contact-plugs receiving the said screws, and the bearing devices for the wheel-shaft having a tubular portion in which the contact-plugs are fitted substantially as set forth. 55

8. The combination with the wheel and its shaft of the harp, devices carried by the harp and provided with bearings for the wheel-shaft and with notches for the branches of the conductor-wire, and the conductor-wire 60 having branches fitting at their ends in the notches of the bearing devices for the wheel-shaft substantially as set forth.

9. The combination of the wheel, its shaft, the contact-plug in the shaft and provided with the branch leading to the wheel, the screws projecting into the ends of the shaft and into contact with the contact-plug therein, the contact-plugs receiving the said screws adjacent to the ends of the shaft, the bearing devices for the shaft having portions receiving the contact-plugs and provided with outwardly-extending tubular portions, the harp-prongs having end slots receiving said tubular extensions, the nut and screw whereby 70 the harp-prongs may be adjusted to bear with more or less tension against the device for supporting the wheel-shaft, and the conductor-wire having branches leading into contact with the said supporting devices substantially 75 as set forth.
